PEEPHOLE BOX

Carl Foster, East St. Louis, Ill., assignor to American Steel Foundries, Chicago, Ill., a corporation of New Jersey

Application March 29, 1943, Serial No. 480,902

7 Claims. (Cl. 126—200)

My invention relates to furnaces and the like and particularly to a device which may be mounted in a wall of a furnace and which may provide a peep hole therethrough affording access to a full view of the interior of the furnace.

A specific object of my invention is to design a member such as above described which may be readily mounted in a wall of a furnace or the like and which may be cooled by means of any suitable liquid which may be circulated therethrough in order to maintain the device at such a temperature that it may be readily used by furnace men without danger of burns.

A further object of my invention is to design a peep hole member having a peep hole therethrough and a liquid chamber therearound, said chamber being provided with inlet and outlet pipes and said peep hole being provided with a cover plate which may be pivotally or slidably mounted in the peep hole member, as desired.

In the drawings, Figure 1 is a front elevation of the preferred embodiment of my novel peep hole device and Figure 2 is a side elevation taken from the left as seen in Figure 1. Figure 3 is a side elevation of the cover plate shown in Figures 1 and 2.

Figures 4 to 7 inclusive show a modified form of my invention, Figure 4 being a front elevation of the peep hole device, Figure 5 being a side elevation taken from the right as seen in Figure 4, Figure 6 being a front elevation of the cover plate and Figure 7 a sectional view taken approximately in the vertical plane bisecting the device as indicated by the line 7—7 of Figure 4.

Describing my invention in detail and referring first to the embodiment thereof shown in Figures 1 to 3 inclusive, my novel peep hole device or box may comprise a plate 2 of any convenient form, here illustrated as substantially rectangular, and said plate may be provided with a round opening 4 therethrough to the margin of which a pipe 6 may be conveniently secured as by welding. A pipe 8 may be mounted around the pipe 6 and may be welded or otherwise secured to the adjacent face of the plate 2, and an annular plate 10 (Figure 2) may be secured as by welding to the ends of the pipes 6 and 8 remote from the plate 2 to define therewith and with said pipes an annular chamber 12, said chamber being liquid tight.

Inlet and outlet pipes 14 and 16 may communicate with the chamber 12 and may be disposed at opposite sides of a plate 18, said plate 18 affording a division wall within the chamber 12 in order to prevent direct circulation of liquid be-

tween the inlet and outlet pipes 14 and 16 as will be readily apparent. It may be noted, as best seen in Figure 1, that the pipes 14 and 16 may be disposed slightly above the bottom of the chamber 12 in order that rust and dirt may collect in the bottom of said chamber without plugging said inlet and outlet pipes. It will be understood that cooling liquid may be forced through the inlet pipe 14 by any convenient means, such as a pump (not shown), said liquid being circulated around the chamber 12 and being afforded an outlet by means of the pipe 16. The plate 2 may be provided with any convenient means such as holes 19, 19 therethrough affording securement therefor to the wall of an associated furnace or the like, and it will be readily apparent that the pipes 6 and 8 will project into an opening through the wall of the furnace to afford a peep hole therethrough. A cover plate 20 may be pivotally mounted at 22 on the plate 2 and may be provided with a handle 24 by means of which the cover may be pivoted to one side of the opening 4, permitting a view of the inside of the associated furnace through the pipe 6 which thus affords a peep hole as above described.

A modification of my invention is shown in Figures 4 to 7 inclusive wherein the peep hole device or box may comprise a plate 52 corresponding to the plate 2 of the previous modification and affording securement for the box to the wall of an associated furnace. The plate 52 may be provided with a round opening 54 therethrough and inner and outer telescoped pipes 56 and 58 may be welded respectively to the margin of the opening 54 and to the adjacent side of the plate 52. An annular plate 60 may be welded to the ends of the pipes 56 and 58 to define therewith and with the adjacent surface of the plate 52 an annular liquid chamber 62 which may be provided with inlet and outlet pipes 64 and 66.

A pair of L-section members 68 and 70 may be welded to the outer face of the plate 52 to define therewith channels for the slidable reception of a cover plate 72 having a handle 74 for convenient actuation thereof, and a bar 76 may be welded to the plate 52 adjacent one end of the members 68 and 70 to afford stop means for the cover plate 72 as it is moved to the left as shown in Figure 4 to closed position over the opening 54. It will be understood that in this embodiment of my invention, similarly to the previous embodiment thereof, a peep hole is provided through the plates 52 and 60 and through the inner pipe 56, affording a view of the interior

of the associated furnace; and cooling liquid may be circulated through the chamber 62 by means of the inlet and outlet pipes 64 and 66 to preserve the device and to maintain the same at a temperature whereby it may conveniently be used by furnace men without risk of burns.

It is to be understood that I do not wish to be limited by the exact embodiments of the device shown which are merely by way of illustration and not limitation as various other forms of the device will, of course, be apparent to those skilled in the art without departing from the spirit of the invention or the scope of the claims.

I claim:

1. In a fabricated peep hole box, a plate with a round opening therethrough, a pipe welded to said plate, another pipe within said first-mentioned pipe and welded to said plate around said opening, said pipes being spaced from each other and defining an annular fluid chamber therebetween, an annular plate spaced from said first-mentioned plate, said second-mentioned plate being welded at its outer and inner perimeters respectively to said first and second-mentioned pipes, and fluid inlet and outlet openings through said first-mentioned plate communicating with said chamber.

2. In a fabricated peep hole box, a plate with a round opening therethrough, a pipe welded to said plate, another pipe within said first-mentioned pipe and welded to said plate around the margin of said opening, said pipes being spaced from each other and defining an annular fluid chamber therebetween, an annular plate spaced from said first-mentioned plate, said second-mentioned plate being welded at its outer and inner perimeters respectively to said first and second-mentioned pipes, fluid inlet and outlet openings through said first-mentioned plate communicating with said chamber, and other openings through said first-mentioned plate spaced from said chamber and formed and arranged for the reception of means for securing said box to an associated furnace wall.

3. In a fabricated peep hole box, a plate with a round opening therethrough, a pipe welded to said plate, another pipe within said first-mentioned pipe and welded to said plate around the margin of said opening, said pipes being spaced from each other and defining an annular fluid chamber therebetween, an annular plate spaced from said first-mentioned plate, said second-mentioned plate being welded at its outer and inner perimeters respectively to said first and second-mentioned pipes, fluid inlet and outlet openings through said first-mentioned plate communicating with said chamber, and a plate between said inlet and outlet openings welded to both of said pipes and to both of said plates to afford a division wall preventing circulation of

fluid between said inlet and outlet openings in one direction around said chamber.

4. In a fabricated peep hole box, a pair of spaced plates with aligned openings therethrough, a pipe welded at opposite ends thereof to respective plates around said openings and affording therewith a peep hole through the box, another pipe surrounding said first-mentioned pipe and welded to said plates, said pipes being spaced from each other and defining therebetween a fluid chamber around said peep hole, and fluid inlet and outlet openings through one of said plates communicating with said chamber.

5. In a fabricated peep hole box, a pair of spaced plates with aligned openings therethrough, a pipe welded at opposite ends thereof to respective plates around said openings and affording therewith a peep hole through the box, another pipe around said first-mentioned pipe and welded to said plates, said pipes being spaced from each other and defining therebetween a fluid chamber around said peep hole, fluid inlet and outlet openings through one of said plates communicating with said chamber, said openings being disposed closely adjacent each other, and a plate between said openings welded to both of said pipes and to both of said plates to afford a division wall preventing circulation of fluid between said inlet and outlet openings in one direction around said chamber.

6. In a fabricated peep hole box, a pair of spaced plates with aligned openings therethrough, a pipe welded at opposite ends thereof to respective plates around said openings and affording therewith a peep hole through the box, another pipe around said first-mentioned pipe and welded to said plates, said pipes being spaced from each other and defining therebetween a fluid chamber around said peep hole, fluid inlet and outlet openings through one of said plates communicating with said chamber, and a plurality of openings through said plate spaced from said chamber, said last-mentioned openings being formed and arranged for the reception of means for securing said box to an associated furnace wall.

7. In a fabricated peep hole box, a pair of spaced plates with aligned openings therethrough, a pipe welded at opposite ends thereof to respective plates, another pipe within said first-mentioned pipe and welded to said plates around said openings to define therewith a peep hole through the box, said pipes being spaced from each other and defining therebetween a fluid chamber around said peep hole, inlet and outlet means for said fluid chamber, spaced guides welded to one of said plates, and a cover slidably mounted in said guides for movement into open and closed position with respect to said peep hole.

CARL FOSTER.
